Patented Aug. 7, 1917.

UNITED STATES PATENT OFFICE.

WILLIAM H. McNUTT, OF NEW YORK, N. Y.

RECEPTACLE.

1,235,987.

Specification of Letters Patent.

Patented Aug. 7, 1917.

Application filed October 8, 1915. Serial No. 54,708.

To all whom it may concern:

Be it known that I, WILLIAM H. McNUTT, a citizen of the United States of America, residing at New York city, in the county 5 and State of New York, have invented certain new and useful Improvements in Receptacles, of which the following is a specification.

My invention relates generally to receptacles especially designed to contain inflammable or explosive liquids, and is concerned particularly with a closure for receptacles of this kind.

The general type of can to which I 15 template applying my invention is that disclosed in United States Letters Patent No. 1,114,165 issued to me October 20, 1914, and my present improvements relate to certain structural features to be hereinafter fully 20 explained.

The principal object of the present invention is to construct the can closure in such a manner as to completely prevent leakage of liquid or escape of vapors from the 25 interior of the can. I accomplish this purpose by a unique construction of the nozzle and cap or cover, whereby these two parts will be complementary to each other in providing the desired tight closure.

Another object of the invention is to simplify the construction of the closure so that the packing gasket, which is provided in the cap to seat against the upper edge of the nozzle, may be readily removed and 35 placed.

A further object of the invention is to provide a novel form of guard for the spring which seats the can closure over the nozzle mouth when the can is not in use.

Other objects of the invention, and its detail structure and operation, will be fully described in the following specification, reference being had to the accompanying drawing, in which—

Figure 1 is a perspective view, partly in section, of a can embodying my improvements;

Fig. 2 is an enlarged vertical sectional view of the nozzle and appurtenant parts of 50 the can; and

Fig. 3 is a perspective view of a spring guard which I may employ.

The present invention is concerned with a type of can having a closure or cap which 55 is normally drawn to its seat by a spring or equivalent means, the cap requiring to be

manually unseated when any of the contents are to be poured from the can. In this way the can is kept in closed condition when not in use so that evaporation and explosion 60 and ignition are avoided.

Referring to the accompanying drawing by reference characters, 10 denotes the can body which may be of any desired form, although the form which I find to be best 65 adapted to the purpose is substantially cylindrical. The upper part of the can is formed with a breast 11 which may be somewhat tapered or conical in form, and has suitably secured thereto, as by spot welding 70 or otherwise, the nozzle 12 which is of cylindrical formation.

Secured to the nozzle 12, and depending well within the can body 10, is a mesh tube 13, the function of which is to prevent ignition or explosion of the can contents, in a 75 manner well-known in this art.

The upper edge 14, of the nozzle 12, is beaded or upset, and presents a surface with which the cap coöperates to provide a 80 tight closure of the can in a manner to be described.

The form of closure which I prefer comprises a substantially circular cap 15 having the depending annular flange 16, the latter 85 being designed to embrace the beaded portion 14 of the nozzle 12. Contained within the cap 15 is a gasket 17 of any suitable substance such as leather, asbestos, raw hide, or the like, the latter being preferable. The 90 gasket 17 is designed to seat tightly against the upper face of the bead 14. Engaging the gasket 17 is a preferably frusto-conical guide 18 which serves to guide the cap 15 into proper position when the same is released by the user of the can. This guide coöperates with the curved inner edge or surface of the bead 14 in causing the cap 15 and gasket 17 to properly seat over the mouth of the nozzle 12.

I prefer to form the cover 15 with a central boss 19 which is telescopically engaged by a supplemental cap 20 having upstanding lugs 21 to receive the lower inturned ends of an operating bail 22.

The entire cap structure including the cap proper 15, the gasket 17, the cone 18, and the supplemental cap 20, is held together by means of the eyelet 23 the upper end of which is threaded and receives the nut 24 110 which is adapted to be screwed down against cap 20.

As heretofore seated, the means for normally forcing the cap 15 to its seat preferably consists of a coiled compression spring, which is engaged by a guard, forming one of the features of my invention which I will now describe.

In Fig. 3 of the drawing, I have illustrated the novel form of guard which serves the treble purpose of connecting the cap structure with the lower end of the mesh tube 13 through the intermediary of a coiled compression spring; preventing the spring itself from being subjected to excessive strains; and also preventing the cap from being pulled out of the can.

The guard comprises the substantially parallel shank members 29^a and 29^b, the intermediate loop member 29^c and the lower hooked member 29^d.

Engaging the eye 25 of the eyelet 23 is an eye 26^a of a link 26, the opposite end of which has a loop or eye 26^b engaging the upper hooked end of the coiled compression spring 27. The lower end of the compression spring is also hooked and engages the intermediate loop 29^c of the guard. It will be noted that the shank 29^a of the guard passes through the eye 26^b of the link 26 and that the opposite shank 29^b is downwardly bent so that the strand between the two shanks forms a stop for the upward pull of the spring.

As appears clearly from Fig. 1, the hook 29^d of the guard engages a stirrup 30 which is held in the lower end of the mesh tube 13, whereby the cap 15 is yieldingly connected to the mesh tube.

Pivotedly supported by lugs 31 on the breast of the can is the carrying bail 32 which may be of any approved construction.

The operation of my invention is as follows:—When it is desired to empty all or a portion of the can contents, the operator grasps the carrying bail 32 and passes one or two fingers through the operating bail 22, this being done while the can is upright. To discharge the contents from the can, the latter is tilted into a horizontal position, as a result of which the cap 15 is unseated, allowing a free flow from the mouth of the nozzle 12. This unseating of the cap and its appurtenant parts takes place against the tension of the spring 27. When sufficient of the contents have been emptied or discharged, the operator simply releases the bail 22, whereby the spring 27 will contract and draw the cap 15 to its seat 14. In this action the cone 18 will coöperate with the curved inner surface of the beading 14 to properly center the cap 15 relatively to the nozzle 12 and cause the flange 16 to truly engage the outer periphery of the bead 14.

One of my aims has been to provide simplicity in the construction of the closure, and it will be observed that I have accom-

plished this by making the assembling and disassembling of the several parts of the cap practically dependent upon the nut 24 and the eyelet 23. If it be desired, for example, to disassemble the parts of the cap closure, it is merely necessary to loosen the nut 24 whereby the eyelet 23 may be withdrawn from the cap, and the several parts of the latter, including the cone guide 18, are free to be separated. This is of importance particularly when it is necessary or desirable to replace the gasket 17, which is subject to considerable wear. The spring 27 may be replaced with equal facility, by disengaging the link 26 from the eye 25, freeing the two ends of the spring 27 from the eyes in which they engage and thereafter, when a new spring has been inserted, again hooking the link 26 into the eye 25.

Having thus described my invention what I claim as new and desire to secure by Letters Patent is:—

1. A device of the character specified, comprising a receptacle having a projecting nozzle, a cap adapted to seat over said nozzle, a fireproof tube depending within said receptacle and co-axial with said nozzle, a spring tending normally to draw said cap to its seat, and a guard coöperatively related to said spring and adapted to prevent excessive strain thereon, said guard having one of its ends connected to said tube and also connected intermediate its ends to one end of said spring.

2. A device of the character specified, comprising a receptacle having a projecting nozzle with a beaded discharge end, a cap for said receptacle having a depending flange adapted to embrace the beaded end of said nozzle, a conical guide adjacent the underface of said cap and projecting into said nozzle, a gasket interposed between the base of said guide and said cap, an eyelet passing through said cap and said guide and adapted to hold the cap, gasket, and guide together, a fireproof tube depending from said nozzle into said receptacle, a link depending from said eyelet, a compression spring having one end thereof engaging said link, and a guard engaging the opposite end of said spring and also engaging said fireproof tube.

3. A device of the character specified, comprising a receptacle having a discharge opening, a cap adapted to close said opening, a fireproof tube within said receptacle, a spring tending to seat said cap over said opening, and a guard to prevent excessive strain on said spring when said cap is raised from said opening, said guard comprising substantially parallel shank members, an intermediate loop engaging said spring, and a hook at one end of said guard whereby the same is connected with the base of said tube.

4. A device of the character specified, comprising a receptacle having a projecting noz-

zle, a cap adapted to seat over said nozzle, an eyelet passing through said cap, a fire-proof tube in said receptacle, a guard having a hooked end connected to the base of said 5 tube, and a loop intermediate its ends, a spring within the tube having one of its ends engaging said loop, and a link having one end engaging said eyelet and its other end engaging the end of the spring opposite that engaged by the loop of the guard. 10
In testimony whereof I have affixed my signature in presence of two witnesses.

WILLIAM H. McNUTT.
